PULL TOY

Henry Gold and Raymond Paul, Chicago, Ill.,
assignors to Ira Gold

Application March 21, 1945, Serial No. 583,876

3 Claims. (Cl. 46—204)

Our invention relates to a pull toy providing movement and sound.

Among the objects of our invention is to provide a pull toy adapted by the movement of the toy to provide further movement associated with the toy and to also provide a series of sounds attractive to juvenile users.

Our invention also contemplates such other objects, advantages and capabilities as will later more fully appear and which are inherently possessed by our invention.

While we have shown in the accompanying drawings a preferred form of our invention, yet we wish it understood that the same is susceptible of modification and change without departing from the spirit of our invention.

Referring to the drawings, Fig. 1 is a front elevational view of our device; Fig. 2 is a side elevational view; Fig. 3 is a top plan view, Fig. 4 is a bottom plan view; Fig. 5 is a detailed sectional view on line 5—5 of Fig. 2; Fig. 6 is a bottom plan view of the inside of the cap; Fig. 7 is a perspective diagrammatic view showing the cord circuit; Fig. 8 is a flat view of a blank from which the housing is formed.

The embodiment selected to illustrate our invention comprises a platform 10, to the under surface of which is attached a pair of spaced supports 11. Each of said supports has an opening 12 adjacent the front. Through said openings 12 rotatably extends a shaft 13, to the opposite ends of which are attached wheels 14. Each of the supports 11, has an opening 12 adjacent the rear. Through said openings 12, rotatably extends another shaft 13, to the opposite ends of which are attached wheels 14.

Substantially in the center of the inner side walls of supports 11, are openings 15 to rotatably receive the opposite ends of spindle 16.

On the front and rear shafts 13 pulleys 17 are mounted at substantially the center thereof. On spindle 16 is also centrally mounted a pulley 18. Each of pulleys 17 has a single groove 19 and pulley 18 has a pair of spaced grooves 20.

A housing 21, preferably simulating a windmill is mounted on the top surface of platform 10. The housing 21 is preferably constructed of cardboard and has bottom flaps 22 adapted to be folded to lie flat on platform 10. A retaining member 23 is then placed over these flaps and attached to platform 10 by suitable attaching means such as nails 24.

The open top of housing 21 is closed by a cap 25. The cap 25 has a hollow interior 26 and a slit 50 in the top portion communicating with said

interior. Extending across this interior 26 is a shaft 27, the inner end of which is rotatably mounted in an opening 58 in the cap 25. The other end of shaft 27 extends through an opening 30 in cap 25 and beyond said cap. Substantially centrally mounted on said shaft 27 within interior 26 of cap 25 is pulley 28 having groove 29.

The outer end of shaft 27 receives the hole 31 of central member 32 of wheel 33 and holds the wheel thereto by friction grip. The outer edge 34 of central member 32 has a plurality of spaced openings 35, to receive the inner ends of spaced rods 36. The outer ends of spaced rods 36, each have attached thereto an end member 37, preferably in the form of a block. Slidably mounted on each of said rods 36 between the central member 32 and the ends 37 is a slidable member 38. The slidable members 38 each have an opening 39 extending therethrough slightly larger than the diameter of the rod.

An endless cord 40 extends around the front portion of the front pulley 17 within groove 19, then extends rearwardly to and around the back portion of the back pulley 17 within groove 19. The cord then extends forwardly to and around the front portion of pulley 18 within one of its grooves 20, upwardly through opening 41 in platform 10 and opening 42 in retaining member 23 through the hollow interior of housing 21 and to and around the upper portion of pulley 28 within groove 29. The cord 40 then extends downwardly from cap 25 through the hollow interior of housing 21 to and around the rear portion of pulley 18 within the other groove 20. The cord 40 then extends forwardly to the front portion of the front pulley 17 to complete the circuit.

In use, when the child moves the toy by pulling on cord 61 attached to the front of platform 10, wheels 14 roll on the floor or other surface. This rotates shafts 13 and turns pulleys 17, and moves cord 40. Cord 40 in turn moves pulley 28 and its shaft 27. The shaft 27 then turns wheel 33. As the wheel 33 turns, slidable members 38 slide as they reach the point of gravity. For example, a slidable member lying against the central member as it passes the line of gravity, falls downwardly on the rod and hits with a sharp clacking sound against the end member. As that same slidable member moves upwardly and passes beyond the line of gravity, it again falls, this time from the end member down against the central member with a crisp sound, attractive to juvenile ears.

Having thus described our invention, we claim:

1. A toy comprising a platform, a pair of sup-

ports attached to and under said platform, a pair of spaced shafts rotatably carried by said supports, wheels attached to said shafts, a spindle rotatably carried by said supports between said shafts, a housing mounted on said platform, a pin rotatably mounted in the upper portion of said housing, one end of said pin extending through and beyond said housing, a hub mounted on said end of said pin, a plurality of spaced spokes having their inner ends attached to said hub, a block attached to the outer ends of each of said spokes, a slideable member mounted on each of said spokes, an endless cord extending between said shafts said spindle and said pin, said shafts adapted to be moved upon the movement of said wheels to move said cord, said cord adapted to move said pin and said pin adapted to move said hub and said spokes, the slideable members on said spokes falling by gravity against the hub and blocks as the center of gravity is passed.

2. A toy comprising a platform, a pair of supports attached to and under said platform, a front and a rear shaft each rotatably carried by said supports, wheels attached to said shafts, a pulley mounted on each of said shafts, a spindle slideably carried by said supports between said shafts, a pulley having spaced grooves mounted on said spindle, a housing mounted on said platform, a pin rotatably mounted in the upper portion of said housing, a pulley mounted on said pin, one end of said pin extending through and beyond said housing, a hub mounted on said end of said pin, a plurality of spaced spokes having their inner ends attached to said hub, a block attached to the outer ends of each of said spokes, a slideable member mounted on each of said spokes, an endless cord extending from the front portion of the pulley on said front shaft rearwardly to and around the back portion of the pulley of said rear

5 shaft, forwardly to and around the front portion of the pulley of said spindle in one of its grooves, upwardly through an opening in said platform and said housing to and around the upper portion of the pulley of said pin, downwardly through said housing and the opening in said platform to and around the rear portion of the pulley of said spindle in the other of its grooves, and forwardly to the front portion of the pulley on said front shaft to complete the circuit, said shafts adapted to be moved upon the movement of said wheels to move the cord, said cord adapted to move said pin and said pin adapted to move said hub and said spokes, the slideable members on said spokes falling by gravity against the hub and blocks as the center of gravity is passed.

10 3. A toy comprising a support, a shaft rotatably mounted on said support, wheels attached to said shaft, said wheels adapted to turn when moved on a surface and to turn said shaft, a pin rotatably mounted on said support and spaced from said shaft, a hub mounted on said pin, a plurality of spaced rods having their inner ends attached to said hub, a stop member attached to the outer ends of each of said rods, a plurality of gravity members, each of said gravity members having an opening therethrough, said opening being larger than said rod but smaller than said stop member, at least one of said gravity members slideably mounted on each of said rods between said hub and said stop member, said cord adapted to be moved upon movement of said shaft, said cord adapted to move said pin and said pin adapted to move the hub and rods, said gravity members on said rods falling by gravity against the hub and stops as the center of gravity is passed thereby imparting an attractive noise.
